UNITED STATES PATENT OFFICE.

WILLIAM HENRY SMITH, OF LA CROSSE, WISCONSIN.

THRASHING-MACHINE.

SPECIFICATION forming part of Letters Patent No. 332,117, dated December 8, 1885.

Application filed June 2, 1885. Serial No. 167,369. (No model.)

To all whom it may concern:

Be it known that I, WILLIAM H. SMITH, a citizen of the United States, and a resident of La Crosse, in the county of La Crosse and 5 State of Wisconsin, have invented certain new and useful Improvements in Thrashing-Machines; and I do hereby declare that the following is a full, clear, and exact description of the invention, which will enable others skilled 10 in the art to which it appertains to make and use the same, reference being had to the accompanying drawings, which form a part of this specification.

My invention relates to thrashing-machines; 15 and it has for its object the construction of a thrashing-machine in which the straw-carriers and their operative mechanism are arranged to operate in such a manner that the straw is fed continuously through and out of the machine, and in which the pivoted grate situated in close proximity to the thrashing-concave is adapted to be adjusted so as to operate 20 to deliver the straw either directly against or under the auxiliary beater, which is also vertically adjustable, for the purpose hereinafter set forth.

To these ends my invention consists in the improved construction and combination of parts of a thrashing-machine, which will be 25 hereinafter fully described, and particularly pointed out in the claims.

Referring to the annexed drawings, Figure 1 is a side view of my improved thrashing-machine, with the side frame of the machine 35 removed in order to show the arrangement of the various parts of the machine; and Fig. 2 is a perspective view with portions of the outer frame or casing broken away.

The same letters of reference indicate corresponding parts in both the figures.

Referring to the several parts by letter, A represents the outer frame or casing of my improved thrashing-machine.

B B' indicate the beater-cylinder and concave, which are of ordinary construction. At 45 the rear end of the concave B' is situated the grating C, which extends entirely across the machine, and is pivotally secured at each upper forward end, as shown, a shaft, C', passing

through the frame A below the grating C, and 50 having secured upon it the eccentric cams C², upon which the rear portion of the said grating rests. The outer end of the shaft C' is provided with an operating-handle, C³, having a spring catch or detent, C⁴, adapted to 55 engage with a toothed segment, C⁵, by which arrangement the cams C² may be secured in their adjusted position, for the purpose herein-after set forth.

The beater-cylinder B is operated from any 60 suitable power by a band passing around a pulley on the outer end of the beater-shaft.

D represents the operating crank-shaft, which is driven through a band from the motive power passing around a pulley on its 65 outer end, the said shaft being provided with the two cranks or wrists D', as shown; or, if desired, only one wrist and one set of operating-levers on the one side of the machine may be employed; but I prefer to use the two sets 70 of levers, as here shown. To each wrist of the crank-shaft is pivotally connected the rear end of the forward pitman, E, and the forward end of the rear pitman, F, the forward end of the forward pitman, E, being pivotally 75 connected to the lower end of the centrally-pivoted elbow-lever G, the upper end of which supports pivotally above its fulcrum the forward end of the forward straw-carrier, H, which is supported at its upper rear end by 80 the hangers I. The forward upper end of the rear pitman, F, is pivotally connected to the lower end of the elbow-lever J, which is pivotally secured at its upper end in the frame A, and has pivotally connected to it at about its 85 center, below its fulcrum, the forward end of the rear straw-carrier, K, which is supported at its rear end by the hangers L.

By reference to the annexed drawings, in conjunction with the foregoing description, it 90 will be seen that when the wrists D' of the crank-shaft are turned forward in the revolution of the same the forward pitman, E, is thrown forward, and, through the centrally-pivoted lever G, serve to swing the forward 95 straw-carrier, H, rearwardly, thus working the straw upon the same to the rear or discharge end of the machine, while at the same time the

rear pitman, F, is drawn forward and operates to swing the rear straw-carrier, K, forward, its inclined teeth or bars sliding beneath the straw, which extends over them. As the 5 wrists of the crank-shaft reach the rearward portion of the space covered by their revolution the motion of the two straw-carriers will be reversed, the rear carrier now operating to work the straw to the rear of the machine, 10 while the forward carrier slides beneath the straw forward to its operative position, the two carriers thus serving to continuously work or carry the straw through and out of the machine. 15 The straw-carriers H and K are each composed of the longitudinal supporting-bars R, formed on their upper sides with the steps R', on which the transverse slats R² are supported in their operative positions, the grain falling 20 from the straw through the spaces between the edges of the several slats. The construction of these straw-carriers is old and well known, and forms no part of my invention. 25 To the rear of the beater-cylinder B, at a suitable distance above the forward end of the forward straw-carrier, H, works the adjustable beater M, the ends of the shaft of which extend through slightly-curved slots M' in the sides of the frame A, and are journaled in segments M², which are pivoted at one end upon 30 the outside of the frame, and are provided at their opposite ends with the teeth M³, adapted to mesh with the adjusting-pinions M⁴, by means of which the segments M², and consequently the ends of the beater-shaft, may be raised or lowered at the will of the operator. When the grain first enters the machine, it passes between the concave B' and the beater-cylinder B, and then over the grating C upon 35 the forward end of the forward carrier, H. By adjusting or turning the shaft C', having the eccentric cams C², previously described, the pivoted grating C may be raised or lowered, so as to direct the straw passing over it either 40 into (that is, directly against and between the teeth) or below the auxiliary beater M, according to the kind of grain being operated upon, rye and similar grain requiring to be thrown directly into or against the beater, in 45 order to separate the grain from the straw, being thus subjected to a greater separating process by the arms of the beater than where the grain is allowed to pass directly upon and over the surface of the forward carrier, and is acted 50 upon by the extremities of the beater-arms alone, which is the course followed with wheat, &c. The vertical adjustment of the beater 55 itself is also for the same purpose.

N indicates the forward lower grain-table, 60 which is pivotally supported at its forward end by the upper arms of the elbow-levers G, as shown, being supported at its rear end by the hanger N', and receiving its reciprocating motion from the levers G. The rear upper 65 grain-table, O, is supported at its rear end by

the hangers O', while its forward portion is supported by the hangers or rods O², connected at their lower ends by the pitmen O³ to the rear end of the forward grain-table, so that the rear grain-table receives its motion also 70 from the lever G through the forward grain-table.

P indicates the fan, which is of ordinary construction.

The operation of my improved thrashing-machine is as follows: The wheat or other grain fed into the forward end of the machine passes through the thrashing-cylinder and over the adjustable grating C, under or against the vertically-adjustable beater M, and is conveyed by the straw-carriers through and out of the rear end of the machine, the carriers operating, as before described, to continuously move or carry the straw. The grain falls upon the grain-tables, and from thence down 85 into a suitable grain-receptacle, Q, the fan P operating to separate the chaff from the grain during its downward passage, as will be readily understood.

From the foregoing description, taken in 90 connection with the accompanying drawings, the construction and operation of my improved thrashing-machine will be readily understood without requiring further explanation.

It will be seen that by constructing and arranging the straw-carriers and their operative mechanism in the manner shown and described the straw is operated upon continuously during its passage through the machine, 100 while the adjustable grating, in conjunction with the adjustable beater, serves to regulate the separating process to which the grain is subjected by the said beater.

Having thus described my invention, what 105 I claim, and desire to secure by Letters Patent of the United States, is—

1. In thrashing-machines, the combination of the operating crank-shaft having one or more wrists, the pitmen arranged on opposite sides of the crank-shaft, the elbow-levers connected at their lower ends to the pitmen, and the straw-carrier tables pivotally connected to the said elbow-levers above and below their fulcrums, respectively, all constructed and arranged to operate in the manner and for the purpose shown and set forth. 110

2. The combination, with the thrashing-cylinder and straw-carriers, of the pivoted adjustable grating and the vertically-adjustable beater, arranged as described, for the purpose set forth. 115

3. As an improvement in thrashing-machines, the combination of the operating crank-shaft, the pitmen arranged to operate 120 on opposite sides thereof, the elbow-levers, arranged as described, the straw-carrier tables pivotally connected to the said levers above and below their fulcrums, respectively, as described, and the grain-tables arranged 125

to be operated through the forward elbow-levers, substantially as shown and described.

4. The combination of the thrashing-cylinder, the pivoted adjustable grating, the straw-carrier tables and their operative mechanism, arranged to operate as described, the vertically-adjustable beater, and the grain-tables, arranged as described, all constructed and arranged to operate in the manner and for the purpose shown and set forth.

In testimony that I claim the foregoing as my own I have hereunto affixed my signature in presence of two witnesses.

WILLIAM HENRY SMITH.
